UNITED STATES PATENT OFFICE

2,478,027

MUSICAL INSTRUMENT BOW

Edwin B. Tichenor, Birmingham, Ala.

Application October 28, 1944, Serial No. 560,764

6 Claims. (Cl. 84—282)

1

This invention relates to bows for playing musical instruments such as violins, cellos, and similar instruments provided with one or a plurality of strings or other vibratory elements.

The main object of the invention is to provide improvements in stringed musical instrument bows in which the hair or other material which may be substituted for hair is fashioned into a simple replaceable unit. To accomplish this purpose, means are provided for holding the hair unit in the bow which will permit the bow to be re-haired in the generally accepted way if no refill covered by the present invention is available, or for any other reason. Also to provide a lower section of the bowhead made of plastic or some other suitable material, having a pre-fashioned pocket or recess to receive one end of the assembled hair in such a manner as to obviate the necessity of cutting, drilling or otherwise carving out such recess in the head in fashioning the bow stick. Also to provide a lower head section of such design as to eliminate the need for the conventional tipping with metal or other material. Also to provide a frog interchangeable with the usual type so that the bow can be re-haired by the generally used method, that is, by knotting the ends of the hair assembly and holding in place in recesses in the head and frog with wooden wedges. Also to provide means for firmly holding the refill of the present invention so as to prevent it from slipping or working out of place, either while the hair assembly is relaxed or taut. Also to provide in the frog end of the refill a slide member with a head the shape of which will cause the slide head to replace the protrusion and covering semi-circular ring found in the conventional frog at the place where the hair emerges from the frog. Also to provide a shape, balance, and feel for the bow, which, to the user, shall not be disconcerting by comparison with the shape, balance, and feel of the conventional type of bow.

Other advantages will appear from the drawing and description.

Referring to the drawing, part of this application, it will be observed that Fig. 1 is a side view of the assembled bow partly cut out, embodying the present invention; Fig. 2 is a side view of the hair unit assembly partly cut out; Fig. 3 is an enlarged side view of the bow head; Fig. 4 is a side view on line 4—4 of Fig. 5 of the bow frog partly in section; Fig. 5 is a sectional view on line 5—5 of Fig. 4; Fig. 6 is a sectional view on line 6—6 of Fig. 7; Fig. 7 is a sectional view

on line 7—7 of Fig. 3; Fig. 8 is an enlarged center sectional view of part of the frog; Fig. 9 is a cross sectional view of the frog on line 9—9 of Fig. 8 assuming that Fig. 8 had its other half; Fig. 10 is an enlarged side view of the slide-in hair retaining member for the bow frog; Fig. 11 is an end view of Fig. 10; Fig. 12 is a view of the head hair retaining plug, Fig. 13, as seen from line 12—12; Fig. 13 is a side view of the head hair retaining plug with hair ends; Fig. 14 is an end view of Fig. 13 as seen from line 14—14; Fig. 15 is a top view of the head plug; and Fig. 16 is a bottom view of the plug with hair ends.

Similar reference numerals refer to similar parts throughout the several views.

Again referring to the drawing in detail it will be seen that the invention comprises a bow stick 1 with hair or substitute material 2, frog 3, and head section 6. The section 6 is attached to the upper portion of the head on the bow stick 1 and is adapted to hold and retain this section 6 by screw 10 means and suitable glue in the joint between the section and the upper portion. The head section 6 is provided with a recess 9 that is of an exact size and shape to receive a plug 5 in which is imbedded or attached one end of the hair 2 assembly. The other end of the hair 2 assembly is imbedded or attached in an enlarged end portion 4 of the slide member 7 adapted to fit into corresponding space 8 with retaining slots or grooves provided in the bottom portion of the frog 3. The head section plug 5 is secured in the recess 9 by a transverse screw 12 that passes through the head section 6 and plug 5 after the plug is inserted in the recess 9. The slide member 7 is held firmly in the frog 3 by means of a screw 13 that is inserted in a suitable hole 11 for same in the slide member 7 and frog 3 when the slide member is inserted. This screw may be one of full or partial length thread.

As will be seen from a consideration of Fig. 16 of the drawing, the hairs are so embedded in the plug 5 as to extend therefrom in ribbon-shape parallelism and thus require no combing out when applying the hair unit to the bow. Also, embedding the hairs in the enlarged end portion 4 of the slide member 7 obviates the necessity of the ferrule and wedge heretofore employed on the frog at the comparable spot to hold the hair flat.

As will be seen further from a comparison of Figs. 4, 5 and 11 of the drawing, the enlarged end portion 4 of the member 7 is of the same size and contour as the adjacent inward end of the frog so that when mounted as shown in Fig. 4 its outer

surfaces merge with the adjacent surfaces of the frog and provide a smooth-surfaced continuation thereof corresponding to the shape of the ferrule heretofore employed in conjunction with a wedge in holding the hair flat. This is important in giving to the bow the same familiar feel and "grip" as are found in bows of the prior art.

From the foregoing it is apparent that the hair and hair holding plug and slide member as shown in Fig. 2 can be produced as a replaceable unit adapted to fit into proper place in the assembled bow by simply attaching with two small screws. Thus when trouble develops in the hair assembly, all that is necessary is to loosen and remove the retaining screws, pull out the plug and slide member with damaged hair, and insert a new unit.

The parts may be made of any material best suited for the purpose and adapted to have the ends of the hair or substitute material as hair imbedded or attached therein, but I prefer to use plastic of a suitable grade.

While I have shown and described the preferred embodiment of my invention, I do not wish to limit same to the exact and precise details of structure, but reserve the right to make all modifications and changes so long as I remain within the spirit and scope of the following claims.

Having described my invention, I claim:

1. In a bow for musical instruments embodying a bow stick, a frog and a head, a hair unit comprising a plug in which one end of the hair is embedded, a screw extending through the plug transversely of the head for securing the plug thereto, there being a recess in the head for receiving the plug, and at the other terminus of the hair an elongated member in one end of which the hair is embedded, there being a longitudinally extending recess in the frog for receiving the elongated member, and means for securing the elongated member to the frog.

2. A device as set forth in claim 1 in which the head is divided into upper and lower sections and in which the lower section is secured to the upper by means of a screw extending upwardly from the bottom of the recess in the head.

3. A device as set forth in claim 2 in which the portion of the elongated member in which the hair is embedded, abuts the inward end of the frog at the recess opening and in which a screw extends upwardly through the elongated member into the frog to anchor it thereto.

4. In a bow for musical instruments embodying a stick having a head at one end and a frog at the other, a head having a portion integral with the stick and a separable portion for securing the hair unit of the bow thereto, said separable portion being separated from the other portion of the head along a plane extending longitudinally of the stick, and having a recess therein for receiving the end of the hair unit, and a screw extending from the bottom of the recess into the other portion of the head for securing the separable portion in place.

5. In a bow as set forth in claim 4, a hair unit having at one end a plug that fits a head recess, the hairs being embedded in this plug and extending therefrom in ribbon-shape parallelism, and in which the plug is held in place in the recess by a screw extending transversely through the separable portion and the plug.

6. In a bow as set forth in claim 5, a hair unit having the hairs at the other end thereof embedded in an enlarged end of an elongated unit, a longitudinally extending tongue and groove connection between the elongated unit and the frog, and a screw passing through the elongated unit into the frog for holding said elongated unit in place.

EDWIN B. TICHENOR.
